US00D959157S

(12) United States Design Patent (10) Patent No.: US D959,157 S
(45) Date of Patent: * Aug. 2, 2022

(54) SMART PHOTO FRAME

(71) Applicant: Shenzhen Yihenke Electronic Technology Co. Ltd., Shenzhen (CN)

(72) Inventor: Chao Peng, Ganzhou (CN)

() Term: 15 Years

(21) Appl. No.: 29/799,753

(22) Filed: Jul. 16, 2021

(51) LOC (13) Cl. 06-07

(52) U.S. Cl.

USPC D6/310

(58) Field of Classification Search

USPC D6/300–314; D10/15, 21, 24; D14/336, D14/371, 374, 375

CPC G09G 2380/16

(57) CLAIM

The ornamental design for a smart photo frame, as shown and described.

DESCRIPTION

FIG. 1 is a first perspective view of a smart photo frame showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion in FIG. 1;

FIG. 10 is an enlarged view of the selected portion in FIG. 2; and,

FIG. 11 is an enlarged view of the selected portion in FIG. 2.

The broken lines shown in the drawings depict portions of the smart photo frame in which the design is embodied that form no part of the claimed design.
